PIVOTED HAND TOOL FOR REMOVING
DENTS IN SHEET METAL

Laurel M. Back, Oakland, Calif.

Application June 3, 1947, Serial No. 752,056

2 Claims. (Cl. 81—15)

1

The invention relates to a hand tool for removing dents from sheets of dentable metal and other materials.

A general object of the invention is to provide an improved tool of the character described which is particularly adapted for removing dents from the fenders of automobiles and other more or less curved sheet members.

Another object is to provide a dent-removing tool which is arranged for a mutual interengagement of cooperative anvil and hammer members carried at the free ends of hingedly connected arms to retain the arms in fixed relation.

A further object is to provide a dent-removing tool which requires no operating clearance beyond its working end and is otherwise operative in a minimum space for its functioning.

The invention possesses other objects and features of advantage, some of which, with the foregoing, will be set forth, or be apparent, from the following description of a typical embodiment thereof and the accompanying drawings, in which

Figure 1 is a side view of a dent-removing tool embodying the present features of invention as operatively applied to a dented plate member.

Figure 2 is a fragmentary front view of the tool showing anvil and hammer elements thereof cooperatively engaging the dented member at the end of a hammer stroke.

Figure 3 is a fragmentary side view showing the anvil and hammer portions of the tool mutually interengaged for maintaining the tool in a preferred non-use condition.

Figure 4 is an enlarged fragmentary and partly sectional side view at the cooperating anvil and hammer parts of the tool.

Figure 5 is a sectional view at the line 5—5 in Figure 4.

Figure 6 is an enlarged fragmentary section taken at the hinge portion of the tool across the hinge axis and in the plane of the tool.

Figure 7 is a section at the line 7—7 in Figure 6.

As particularly illustrated, the features of my invention are incorporated in the structure of a dent-removing tool 9 having cooperative anvil and hammer members 11 and 12 respectively provided at the free ends of arms 13 and 14 which are hingedly connected at their other ends at a hinge assembly 15. Preferably, and as shown, the arms 13 and 14 are continuously curved away from each other in a common plane in which they are relatively swingable about an axis perpendicular to said plane. The hinge assembly 15 permits a mutual separation of the anvil 11 and hammer 12 to receive a dented mem-

2

ber or work-piece 16 between them for their mutual swinging application to a dent, or offset, portion 16' of the member 16 for flattening out the portion 16' to conform with the adjacent undented plate part.

The present arms 13 and 14 are tubular, and the anvil and hammer members 11 and 12 respectively are shown as provided with threaded stems 11' and 12' for fixed threaded engagement in the arm ends whereby these members are replaceable if and when required. The anvil 11 essentially comprises a plate member 17 at the end of the stem 11', the latter being shouldered at the base of its threaded portion for the abutment of its shoulder with the end face of the arm 13 when the anvil is mounted on the arm. The hammer 12 provides a point portion 18 having a tip 18' of suitable form for engagement with the dent portion 16' of the workpiece 16 while the latter is engaged against the opposed anvil face; this element may be of one-piece construction having a nut-shaped flange 12'' at the juncture of its threaded and point portions for use in mounting and dismounting it with respect to the end of the arm 14, said flange abutting the extremity of the arm 14 when the hammer is fixed on the arm.

It will now be noted that the work-engaging face 17' of the present anvil plate 17 is coplanar with the axis of hinging of the arms 13 and 14, and that said plate is rectangular and extends slightly forwardly of the anvil stem 11' to an edge 17'' which is parallel to the axis of hinging of the arms. A cylindrically curved notch 19 extends into the plate 17 transversely therethrough from its forward edge 17'' with the axis of curvature of the notch lying substantially in the line of said edge, and the hammer tip 18' is arranged to swing in an arc which passes through said axis substantially at the working face 17' of the anvil plate 17; in this manner, the hammer tip 18' is arranged to move against the projecting side of the dent portion 16' in a line perpendicular, or normal, to the portion of the workpiece which is backed by the plate 17 for preventing an angular action of the hammer tip with respect to the workpiece.

It will be understood that the notch 19 not only facilitates a return displacement of the material at a dented portion backed by the anvil for engagement by the hammer, but also serves as a sight opening for appropriately locating the anvil 11 with respect to a dent to be removed by its flattening out. Furthermore, the present notch 19 is large enough to receive the extremity

of the arm 14 at the hammer whereby the arm may be manually sprung outwardly to engage its extremity in the notch and dispose the flange 12' of the hammer at the back of the anvil plate 17 to secure the arms together thereat for facilitating a storage or shipping of the tool; this non-use engagement of the arms is shown in Figure 3.

It will now be particularly noted that all forward parts of the present tool lie within an arc including the line of the front edge 17' of the anvil plate 17 and having its center at the axis of hinging of the arms 13 and 14. With this arrangement, any dent which may be engaged between the anvil and hammer point of the closed tool may be flattened out by repetitively swinging the hammer point against it, provided only that there are no obstructions to the working swinging of the arm 14.

The present continuously curved and oppositely arched form of the arms 13 and 14 are such that they provide no projections laterally outwardly thereof and have their curvatures so varied therealong as to best provide for the working positioning of the tool and its actuation in its working position. To provide the desired clearance beyond the working end of the tool at the anvil, the forward ends of the different arms define acute angles with radii to the axis of swinging of the arms from the anvil face 17', and from the hammer tip 18'; in the present structure, said acute angles are of the order of fifty degrees and eighty degrees respectively. Since working strokes of the hammer against a dent may be relatively short, the present tool may have its hammer operatively applied in particularly confined spaces such as those beneath the fender of an automobile.

It will now be noted that the hinge assembly 15 is preferably such that the working tip 18' of the hammer 13 is held to a fixed path in its movements toward or from a workpiece engaged by the anvil face 17', whereby to insure a spot or "bull's-eye" application of the tip 18' against the outside of the cup of a dent; accordingly, the bearing of the hinge assembly 15 is preferably relatively long, and a hinge structure with such a bearing is provided in the present tool. As particularly shown, the rearward end of the arm 13 is provided with a pair of inturned ears 21 in mutually parallel spaced relation and arranged to receive between them spaced ears 22 extending outwardly from the arm 14, said ears rotatably and closely receiving a tubular hinge-pin 23 in mutually aligned bearing holes provided through them. The pin 23 mounts a spacing sleeve thereon between the ears 22 of the arm 14, and screws 25 threadedly engaged in the bore of the tubular hinge-pin 23 have their heads 25' extending opposite the outer sides of the ears 21 and engage the pin ends to secure the hinge pin to the ears 21 in its operative relation to the hinge assembly.

In the present hinge assembly, the lubrication of the bearing provided between the exterior of the pin 23 and the holes in the ears 22 is arranged to be affected from within the pin. Accordingly, and as shown, the central portion of the bore of the pin 23 between the opposed inner ends of the screws 25 is arranged to contain a lubricant grease or heavy oil, and the pin is provided with radial holes 23' thereat for permitting an escape of the grease within the bore of the sleeve 24 along which it may travel to the bearings of the ears 22 for maintaining a lubricated condition for the hinge assembly.

The present hinge assembly is also provided with a suitable stop means for limiting the angular separation of the arms 13 and 14. As particularly shown, shoulders 26 provided on the ears 22 of the arm 14 are engageable with the inner ends of the arm 13 when the arms are separated to the maximum degrees illustrated in Figures 1 and 6, it being noted that the inner end of the tube of the arm 13 is flattened and that the ears 21 are integrally fixed to its sides thereat, as by welding.

Having a structure as so far described, it will be understood that an operator may hold the arms 13 and 14 in his different hands and move them toward and from each other for effecting hammering and return movements of the hammer head with respect to a work-piece which is backed by the anvil 11. In accordance with the present invention, however, means are provided whereby the present tool may be positioned and operated by the use of solely one hand. As particularly shown, a handgrip 27 extends beyond the ears 22 of the arm 14 as a general continuation or extension of the arm, said grip member lying within and opposite the inner end portion of the arm 13 in such relation thereto that an operator may simultaneously grasp said arm portion and the grip in a hand and draw the members together for providing a working stroke of the hammer. The outer line of the grip 27 is preferably complementary to the inner line of the opposed portion of the arm 13, and is so related to the latter that it approaches coincidence with it as a working stroke is completed. The grip 27 may be rubber-covered as indicated.

It will now be noted that when the present tool is disposed in an upright plane with the arm 13 uppermost, as in Fig. 1, the arm 14 will be gravitationally urged to its lower, or withdrawn, position, and that working strokes of the hammer may be simply effected by alternately closing and opening a hand engaged about the grip 27 and the complementary grip provided by the rearward portion of the arm 13. The present tool will not, however, always be used in the position particularly shown, and for that reason a spring means is preferably provided for yieldingly urging the permitted limited separation of the arms. As particularly shown, a U-spring 28 is engaged about the sleeve 24 and has its ends so engaging the arms 13 and 14 as to yieldingly urge the angular separation of the arms to a degree which permits a hand-grip working stroke while insuring the normal separation of the arms when the grip of the hand is released. The present spring 28 is of wire and comprises generally parallel side bends 28' connected by a bend 28'' at the ends thereof which engage the arm 13.

From the foregoing description taken in connection with the accompanying drawings, the advantages of the present dent-removing tool features will be readily understood by those skilled in the art to which the invention appertains. While I have described the principle of operation, together with an arrangement which I now consider to be a preferred embodiment thereof, I desire to have it understood that the showings are primarily illustrative, and that such changes and developments may be made, when desired, as fall within the scope of the following claims.

I claim:

1. A tool for removing a dent from a sheet of malleable material, comprising a pair of resilient arms hingedly connected at their rear ends and

arranged to receive a dented sheet portion between them, a spring means resiliently urging a mutual separation of the arms, an anvil plate rigidly fixed upon the forward end of one arm and providing a working face disposed opposite the sheet at its indented side adjacent its dented area and provided with a notch extending inwardly from its forward end, a hammer mounted upon the forward end of the other arm as a longitudinal extension thereof and having a radial flange at the base of its head projecting inwardly beyond the extension of the other arm and arranged for swinging with the arm to operate its working head against the outset sheet portion at the dent while said plate is disposed opposite the dent, the hammer-carrying arm being engageable in the notch of the anvil with the flange of the hammer engaged with the opposite side of the anvil plate from its working face for a retention of the hammer and plate in engaged relation under the action of the spring means.

2. A tool for removing a dent from a sheet of malleable material, comprising a pair of arms hingedly connected at their rear ends and arranged to receive a dented sheet portion between them, an anvil block rigidly fixed upon the forward end of one arm and providing a working face disposed opposite the sheet at its indented side

10

20

adjacent its dented area, and provided with an open segmental notch extending inwardly from its extreme forward end, and a hammer mounted upon the forward end of the other arm and arranged for swinging with the arm to operate its working head against the outset sheet portion at the dent while said block is disposed opposite the dent, the line of action of the hammer head passing through said notch of the anvil midway of its sides and all portions of the arms and hammer lying radially inwardly of an arc having its center in the hinging axis of the arms and passing through said extreme forward end of the anvil block.
